[57] CLAIM

The ornamental design for a bed storage compartment, as shown and described.

DESCRIPTION

FIG. 1 is a perspective view of the bed storage compartment;

FIG. 2 is a rear view of the bed storage compartment;

FIG. 3 is a front view of the bed storage compartment;

FIG. 4 is a right side view of the bed storage compartment;

FIG. 5 is a left side view of the bed storage compartment;

FIG. 6 is a top view of the bed storage compartment; and,

FIG. 7 is a bottom view of the bed storage compartment.

The broken lines are for environmental purposes only and form no part of the claimed design.
